AUDIOMETER TEACHING DEVICE

Herbert N. Hartman, New York, and Samuel I. Berger,
Brooklyn, N.Y., assignors to Biocoustics, Inc., Rock-
ville, Md.

Filed June 29, 1970, Ser. No. 23,703

Term of patent 14 years

Int. Cl. D19—08; D14—02
U.S. Cl. D25—1

FIG. 1

FIG. 2

FIG. 3

FIG. 4

FIG. 5

FIG. 6

FIG. 1 is a front perspective view of the audiometer teaching device with the lid in raised position showing our new design;

FIG. 2 is a top plan view thereof with the lid in closed position;

FIG. 3 is a right side view thereof with the lid in closed position;

FIG. 4 is a front view thereof with the lid in closed position;

FIG. 5 is a bottom plan view thereof;

FIG. 6 is a back plan view thereof with the lid in closed position.

The left side is the same as the right side shown in FIG. 3.

We claim:

The ornamental design for an audiometer teaching device, shown and described.
